2 SHEETS—SHEET 2.

UNITED STATES PATENT OFFICE.

CHARLES H. GUNN, OF OAKLAND, CALIFORNIA.

COMBINATION BED, TABLE, AND SETTEE.

1,399,342.

Specification of Letters Patent.

Patented Dec. 6, 1921.

Application filed January 22, 1921. Serial No. 439,070.

To all whom it may concern:

Be it known that I, CHARLES H. GUNN, a citizen of the United States, residing at Oakland, county of Alameda, State of California, have invented certain new and useful Improvements in Combination Beds, Tables, and Settees; and I do declare the following to be a full, clear, and exact description of the same, reference being had to the accompanying drawings, and to the characters of reference marked thereon, which form a part of this application.

This invention relates to improvements in household furniture, and particularly to a type especially suited for apartment houses, flats, and any home in which furniture space is limited or the number of occupants is relatively great.

The principal object of the invention is to provide an article of furniture in which a table, a bed and a settee will be combined in a single and compact unit.

Another object is to provide a minimum of operating parts or mechanisms, so that to convert the article from a table to a bed, or arrange it to serve as a commodious settee, will be but the work of a few seconds.

The device may of course be built in different sizes so as to provide a large "family" table in combination with a full length bed, or it may be made to serve as a side table and a child's crib.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Figure 1 is a perspective elevation of the device, showing the same in use as a table.

Fig. 2 is a similar view, showing the table top opened out to disclose the bed portion of the device.

Fig. 3 is a perspective elevation of the device turned to serve as a settee.

Fig. 4 is a longitudinal section, showing half the table top in place as such and half opened up or moved to serve as the head or foot rest of the bed.

Fig. 5 is an enlarged fragmentary section

of a table-top members, showing a catch or lock system.

Referring now more particularly to the characters of reference on the drawings, the numeral 1 denotes the permanent end pieces or panels of the structure, having connecting side boards 2 extending down from the top edges, a relatively short distance, from the lower edges of which bottom boards 3 slope downwardly at a slight angle toward the longitudinal center, while from the junction of these boards along said central plane a rigid board 4 depends downwardly to the bottom of the panels 1.

The parts thus far described form a rigidly secured and permanent structure, and it will be noted that the members 1, 2 and 3 define a rectangular area in the bottom of which may be placed a spring mattress 5 of any desired form, extending from end to end of the inclosure, which serves as a bed, and can of course be made in various sizes to suit different conditions.

It will also be seen that by tipping the entire structure onto its side, the member 4 forms the seat of the settee, the slanting boards 3 providing the back, while the members 1 form the end arm-rests. The member 4 is only intended to be used as a seat on one side thereof, and slopes downwardly (when positioned as a seat) from its outer to its inner end, so as to add to the occupant's comfort. It may also be provided with permanently mounted cushions if desired, together with the back 3.

To permit the device to be readily upset from the bed to the settee position, or vice-versa, the corners of the panels 1 on which the device tilts are provided with casters 6 which bear on the floor at all positions of the said panels.

Adapted to completely cover the bed area and resting on top of the members 1 and 2 are a pair of identical table-top members 7, abutting together along the transverse center line of said area and preferably extending somewhat beyond the members 1 and 2 for the sake of appearance.

These table members are each connected to the members 2 by a pair of links 8, pivoted to the under side of the top and to the inside of the members 2, the length and pivotal connections of these links being so proportioned and arranged that when the top to which they are connected is pulled away

from the adjacent top, it may be moved to lie vertically and directly adjacent the outer face of the corresponding end panel, the adjacent ends of the links then resting on 5 said panel, and the portion of the top projecting thereabove serving as the head or foot board of the bed. In order to bring about these conditions, the pivotal connection of the links with the members 2 must 10 be placed substantially half-way between the pivotal connection of the links with the table top and the outer face of the corresponding end-panel.

In order to hold each table top in rigid 15 connection with the members 1 and 2 and against undesired movement either when the table is being used as such or when the structure is upset to serve as a settee. I provide a plurality of notched lugs or catches 9, pivotally mounted in said top and projecting therebelow a certain distance, and adapted 20 to project into and engage with slotted plates 10 set flush with the upper edges of the members 1 and 2. There is preferably 25 one such catch at each inner end of the table top, one of which has a spring 11 serving to normally hold such catch in positive contact with its slotted plate, the corresponding plates being fixed in the members 2, and one 30 adjacent the outer edge, the plate 10 therefor being set in the end panel 1. These catches automatically engage their respective plates when the tops are moved to lie and rest on the members 1 and 2. To release all the catches on each top in unison, 35 and at will, a finger trigger 12 is provided, this being slidably mounted in the top 7 and projecting into a recess 13 positioned on the under side of said top in that portion, projecting beyond the end panel 1. A pull wire 40 14 extends from said trigger to the adjacent catch, and wires 15 branch from said catch to the other catches at the other end of the top, these wires being preferably set in concealed or covered grooves 16.

Thus it will be seen that by pulling on the single trigger, all three catches are simultaneously moved to disengage the slotted plates, and while so moved, the table top 50 may be raised a trifle and drawn toward the party operating and standing behind the

trigger, this manipulation of the table causing an upward movement at the same time on account of the links, which then support the majority of the weight of the top and 55 allow it to be easily moved to lie against the end panels. As soon as the catches are free of the slots, the trigger may be released, when the springs 11 will work to move the catches back to the position in which they 60 will automatically engage the slotted plates when the table tops are re-positioned.

From the foregoing description it will be readily seen that I have produced such a device as substantially fulfills the objects of 65 the invention as set forth herein.

While this specification sets forth in detail the present and preferred construction of the device, still in practice such deviations from such detail may be resorted to as do 70 not form a departure from the spirit of the invention, as defined by the appended claims.

Having thus described my invention, what I claim as new and useful and desire to secure by Letters Patent is:

1. In a combination bed and table comprising side and end panels inclosing a bed area and a pair of table tops adapted to rest on the panels to cover such area or to be moved to lie vertically outside the end panels, there being one catch at the outer end of each top and catches on each side adjacent the other end, members mounted in the panels and with which said catches engage, a finger trigger mounted at the outer end of each top and located adjacent to the catch at that end, a direct connection from said trigger to said catch, and connections branching from said catch to the catches at the other end.

2. In a combination bed and table comprising a frame inclosing a bed area and a pair of table tops adapted to rest on the frame to cover such area or to be moved to lie vertically outside the ends of the frame, 95 a catch at one end of each top, catches on each side thereof adjacent the other ends, the catches being adapted to engage the frame, and a common means in each top for releasing all the catches thereon simultaneously.

In testimony whereof I affix my signature.
CHARLES H. GUNN.
